(57) **CLAIM**

The ornamental design for a six fold game board, as shown and described.

DESCRIPTION

This application is being filed concurrently with U.S. Utility patent application Ser. No. 12/217,832, entitled Six Fold Game Board And Method of Folding Game Board, filed on Jul. 9, 2008.

FIG. 1 is a perspective view of a six fold game board embodying the present invention, showing the game board in a fully open position;

FIG. 2 is a perspective view showing the game board after one fold;

FIG. 3 is a perspective view showing the game board after two folds;

FIG. 4 is a perspective view showing the game board after three folds;

FIG. 5 is a perspective view showing the game board after four folds;

FIG. 6 is a perspective view showing the game board after five folds, its fully closed position;

FIG. 7 is a further perspective view of the game board showing the game board showing the cut lines between the outer segments which permit folding;

FIG. 8 is a perspective view of a second embodiment of the six fold game board embodying the present invention, showing the game board in a fully open position;

FIG. 9 is a perspective view showing the game board after one fold;

FIG. 10 is a perspective view showing the game board after two folds;

FIG. 11 is a perspective view showing the game board after three folds;

FIG. 12 is a perspective view showing the game board after four folds;

FIG. 13 is a perspective view showing the game board after five folds, its fully closed position; and,

FIG. 14 is a further perspective view of the game board showing the game board showing the cut lines between the outer segments which permit folding.
